UNITED STATES PATENT OFFICE.

CHARLES SCHENCK, OF CHICAGO, ILLINOIS, ASSIGNOR TO ELEVATOR SUPPLY & REPAIR COMPANY, OF CHICAGO, ILLINOIS, A CORPORATION OF ILLINOIS.

LUBRICATOR FOR ELEVATOR-GUIDES.

1,020,715.

Specification of Letters Patent. Patented Mar. 19, 1912.

Application filed December 1, 1910. Serial No. 595,094.

To all whom it may concern:

Be it known that I, CHARLES SCHENCK, a citizen of the United States, and a resident of Chicago, county of Cook, and State of Illinois, have invented certain new and useful Improvements in Lubricators for Elevator-Guides, of which the following is a full, clear, and exact description.

The invention relates to lubricators for elevator guides of the type adapted to be carried by the car to automatically lubricate the guides as the car travels. Lubricators of this sort have heretofore comprised oil receptacles with wicks leading therefrom and suitable springs for yieldingly holding the wicks into engagement with the surfaces of the elevator guide. Such prior constructions are efficient, since the wicks economically feed the oil by capillary attraction, and since a number of wicks may be used to lubricate the surfaces of the guide. But in such constructions the wicks directly engage the guide surfaces and hence, are rapidly worn out.

In accordance with the present invention, the lubricator is provided with shoes which are spring pressed into engagement with the surfaces of the guide and wicks leading from the oil receptacle feed the oil to the guide engaging surfaces of the shoes. These shoes are formed of non-abrasive material, such as fiber, soft metal or the like, so that they will not injure the finished surfaces of the metal guides. Preferably, also, the shoes are provided with wick receiving openings extending to the guide engaging surfaces thereof and the wicks are securely held within the openings and are protected by the shoes so that they cannot wear out.

The preferred embodiment of the invention is hereinafter set forth, illustrated in the accompanying drawings and the essentials of the invention are more particularly pointed out in the appended claims.

In the drawings, Figure 1 is an elevation of the improved lubricator with parts in section on the line 1—1 of Fig. 3. Fig. 2 is a vertical section on the line 2—2 of Fig. 1. Fig. 3 is a horizontal section on the line 3—3 of Fig. 1 and Fig. 4 is a horizontal section on the lines 4—4 of Figs. 1 and 2.

As shown, the body of the lubricator preferably comprises a U-shaped receptacle 10

adapted to extend about the elevator guide 11, as most clearly shown in Figs. 3 and 4. 55 The receptacle is provided at its lower end with perforated ears or lugs 12 for receiving suitable fastening screws by which it is secured to the guide engaging shoe or other suitable part of the car in proper relation 60 to the guide. A removable cap 13 is provided for closing the upper end of the receptacle. As shown, this cap is connected to the body of the receptacle by a chain 14 and is held in position upon the upper end of 65 the receptacle by a suitable fastening device. In the form shown, the fastening device comprises a projecting screw 15 that is engaged by a bifurcated lug 16 on the cap and a clamp nut 17 threaded on the screw and 70 arranged to engage the lug 16. The recessed portion of the U-shaped receptacle is provided, at its lower portion, with walls 18, so that a reservoir is provided for the lubricant or oil. 75

The guide engaging shoes 19 and 20 are preferably mounted within the upper portion of the receptacle upon a series of pins 21 which are fixed to the walls of the receptacle and project inwardly therefrom. As 80 shown, the pins are square in section and the shoes 19 and 20 are provided with similarly shaped openings, so that the latter are held against twisting. The shoes are provided with broad guide engaging faces 85 which fit upon and slidably engage the surface of the elevator guide. In the form shown, the shoes are provided with flat surfaces arranged to engage the corresponding surfaces of the guide 11, the shoes 19 engaging the side faces of the guide and the narrower shoe 20 engaging the edge face thereof. A series of springs 22 coiled about the pins 21 extend between the walls of the receptacle 10 and the shoes 19 and 20, so that 90 the latter are pressed into engagement with the elevator guide. 95

The shoes 19 and 20 are preferably formed of fiber, but may be formed of soft metal or other suitable non-abrasive material which 100 is relatively soft as compared with the steel or wrought iron elevator guide.

A series of wicks 23, formed of suitable textile material, such as heavy flannel or the like, lead from the oil reservoir in the 105 lower portion of the receptacle and extend

2 through suitable openings in the shoes to the guide engaging surfaces thereof. These openings preferably comprise grooves formed in the guide engaging faces of the shoes 19 and 20 and within which grooves the upper portions of the wicks are compressed and securely held. The wide shoes 19 that engage the sides of the guide are preferably provided with two oppositely 10 inclined, transverse grooves 24 connected by a vertical groove 25 and through which the upper folded portions of the wicks extend. The narrow block 20 that engages the edge face of the guide has a vertical groove 26 in 15 its face, the lower end of which communicates with an inclined hole 27 extending through the body of the shoe at its lower end. The side edges of the grooves 24 and 26 are preferably under-cut, that is to say, 20 the openings of the grooves upon the surfaces of the wick-holders are narrower than the main portions thereof, as indicated in the drawings. These grooves are of such size that, when the wicks are compressed 25 therein, the latter are securely gripped and held in proper relation to the shoes and to the elevator guide.

In operation, the guide engaging surfaces of the shoes or wick-holders 19 and 20 and 30 the surfaces of the guide 11 are at all times thoroughly coated with oil or lubricant which is drawn from the reservoir by the wicks 23. The shoes, as stated, are preferably formed of fiber or other suitable non-abrasive material, which is relatively soft 35 as compared with the steel elevator guides, so that the surfaces of the guides are not injured by the rubbing contact thereof. The wicks are so arranged that they cannot 40 readily wear out and do not have to be frequently renewed. The arrangement of the grooves 24 and 26 in the wick-holders or shoes is such that the wicks 23 all extend from the outer portion of the oil receptacle 45 inwardly toward the shoes and the upper portions of the wicks are compressed and securely gripped within the grooves of the shoes and cannot be displaced from proper position. The portions of the wicks 23 in 50 the oppositely inclined grooves 24 of the shoes 19 rub over the side bearing faces of the elevator guide 11 and serve to deflect the oil toward the opposite edge portions of these faces and thus properly distribute it 55 over all portions thereof.

It is obvious that numerous changes may be made in the details set forth without the departure from the essentials of the invention as defined in the claims.

60 I claim as my invention:

1. A lubricator for elevator guides, comprising an oil receptacle adapted to be fixed to the car, a shoe movably mounted on said receptacle, said shoe being formed of non-abrasive material and having a flat face ar-

ranged to slidably engage the surface of the elevator guide, a wick leading from said receptacle and fixed at one end to said shoe for feeding oil to the guide engaging surface thereof, and a spring for pressing said shoe into engagement with the guide, substantially as described.

2. A lubricator for elevator guides adapted to be carried by the car and comprising an oil receptacle, a movable shoe formed of 75 non-abrasive material and arranged above the oil level of said receptacle, a spring for pressing said shoe into engagement with the surface of the elevator guide, and a wick leading from said receptacle to said shoe 80 for feeding oil by capillary attraction to the guide engaging surface of the shoe, substantially as described.

3. A lubricator for elevator guides adapted to be carried by the car and comprising a 85 lubricant receptacle, a wick leading from said receptacle, a movable wick-holding shoe formed of non-abrasive material and having a face arranged to slidably engage the elevator guide, said shoe having a plurality of transverse grooves in its guide engaging 90 surface through which said wick extends, and a spring for pressing said shoe toward the elevator guide, substantially as de- 95 scribed.

4. A lubricator for elevator guides comprising an oil receptacle adapted to be fixed to the car, a relatively movable shoe formed of fiber and having a flat surface arranged to engage the surface of the elevator guide, a spring for pressing said shoe into engagement with the guide, and a wick extending from said receptacle to said shoe for feeding oil to the guide engaging surface of the shoe, substantially as described.

5. A lubricator for elevator guides comprising an oil receptacle adapted to be carried by the car, a movable shoe formed of fiber and having a flat surface arranged to engage the surface of the elevator guide, said shoe being arranged above the level of the level of the oil in said receptacle, a spring for pressing said shoe into engagement with the guide and a wick leading from said receptacle to said shoe for feeding oil by capillary attraction to the guide engaging surface of the shoe, substantially as described.

6. A lubricator for elevator guides adapted to be carried by the car comprising a U-shaped receptacle adapted to extend about the guide and having an oil reservoir in its lower portion, a series of three wick-holding shoes formed of relatively soft, non-abrasive material movably mounted in the upper portion of said receptacle and having flat surfaces arranged to engage the surfaces of the elevator guide, and also having wick receiving openings extending to the guide engaging surfaces thereof, springs for pressing

- said shoes toward the guide and wicks leading from said oil reservoir and extending through the openings of said shoes, substantially as described.
- 5 7. A lubricator for elevator guides adapted to be carried by the car and comprising a U-shaped receptacle adapted to extend about the guide and having an oil reservoir in its lower portion, a series of wick-holding 70 shoes formed of fiber and having flat surfaces arranged to engage the surfaces of the elevator guide, said shoes being movably mounted in the upper portion of said receptacle and having grooves formed in the 75 guide engaging surfaces thereof, wicks extending from said oil reservoir, the upper portions of said wicks being compressed and securely held within the grooves of said shoes and springs for pressing said shoes toward the guide, substantially as described.
- 10 8. A lubricator for elevator guides adapted to be carried by the car and comprising a U-shaped receptacle adapted to extend about the guide and having an oil reservoir in its lower portion, a series of three wick-holding 80 shoes formed of relatively soft, non-abrasive material and having surfaces conforming to and arranged to engage the surfaces of the elevator guide, a series of pins in the upper portion of said receptacle whereon said shoes are slidably mounted, springs for pressing said holders into engagement with said guide, said shoes having grooves in the 85 guide engaging surfaces thereof, and a series of wicks extending from said oil reservoir and having their upper portions compressed within and securely held in the grooves of said blocks, substantially as described.
- 15 9. A lubricator for elevator guides comprising an oil receptacle adapted to be fixed to the car, a wick holding the shoe movably mounted upon the body of said lubricator, said shoe being formed of relatively soft, 90 non-abrasive material and having a surface conforming to and arranged to engage the surface of the elevator guide, said shoe also having a wick receiving opening extending to the guide engaging surface thereof, and a 95 spring for pressing said shoe into engagement with the guide, substantially as described.
- 20 10. A lubricator for elevator guides comprising a lubricant receptacle, a wick-holding shoe movably mounted upon the body of the lubricator, said shoe being formed of relatively soft, non-abrasive material, having a surface conforming to and arranged to engage the surface of the elevator guide, 100 and also having two transverse, oppositely inclined, grooves in its guide engaging surface, a wick extending from said oil reservoir and having a folded upper portion extending through and securely held within 105 said transverse grooves, and a spring for pressing said shoe toward the guide, substantially as described.
- 25 11. A lubricator for elevator guides comprising an oil receptacle adapted to be fixed to the car, a movable wick holding shoe 70 formed of relatively soft, non-abrasive material and having a flat surface arranged to engage the surface of the elevator guide, said shoe also having an opening extending to the guide engaging surface thereof, a 75 wick leading from said receptacle and extending through the opening of said shoe, and a spring for pressing said shoe toward the guide, substantially as described.
- 30 12. A lubricator for elevator guides comprising an oil receptacle adapted to be fixed to the car, a movable wick holding shoe arranged above the level of the liquid in said receptacle, said shoe being formed of fiber and having a flat surface arranged to engage the elevator guide and having a groove extending across said guide engaging surface, a wick leading from said receptacle and having its upper end compressed and securely held within the groove of said shoe, 90 and a spring for pressing said shoe toward the guide, substantially as described.
- 35 13. A lubricator for elevator guides, adapted to be carried by the car and comprising a U-shaped receptacle adapted to be fixed to the car and extending about the guide, a series of three shoes movably mounted on said receptacle, said shoes being formed of non-abrasive material and having flat faces arranged to engage the opposite side and edge faces of the elevator guide, and wicks leading from said receptacle and each fixed at one end to one of said 95 shoes for feeding oil to the guide engaging surface thereof, substantially as described.
- 40 14. A lubricator for elevator guides comprising a receptacle adapted to be fixed to the car, a plurality of relatively movable shoes formed of fiber and having flat surfaces and having faces arranged to engage the faces of the elevator guide, springs for pressing said shoes into engagement with said elevator guide and wicks leading from said receptacle to said shoes for feeding the oil to the guide engaging surfaces of said 100 shoes, substantially as described.
- 45 15. A lubricator for elevator guides adapted to be carried by the car and comprising a U-shaped receptacle adapted to extend about the guide, a series of three 110 spring pressed shoes formed of non-abrasive material and arranged to engage the opposite side and edge faces of the elevator guide, and wicks leading from said receptacle to said shoes for feeding the oil to the guide 115 engaging surfaces thereof, substantially as described.
- 50 16. A lubricator for elevator guides comprising a U-shaped receptacle adapted to be fixed to the car and extend about the guide

a series of three relatively movable shoes formed of fiber and arranged to engage the opposite side and edge faces of the elevator guide, springs for pressing said shoes into engagement with the guide, and wicks leading from said receptacle to said shoes for feeding the oil to the guide engaging sur-

faces of the shoes, substantially as described.
